[57] CLAIM

The ornamental design for a beauty box, as shown and described.

DESCRIPTION

FIG. 1 is a perspective view from the front and the left of a beauty box with the cover in the open position showing my new design.

FIG. 2 is a perspective view from the front and the right of the beauty box with the cover in closed position.

FIG. 3 is a bottom perspective view of the beauty box of FIG. 2.

FIG. 1

FIG. 3
